CHAIR WITH SELF-ADJUSTING BACK

Homer E. Smith and William B. Beuhler,
Indianapolis, Ind.

Application October 20, 1948, Serial No. 55,608

4 Claims. (Cl. 155—161)

1

This invention relates to a chair of the so-called self-adjusting type in which the inclination of the chair-back may be changed merely by the occupant's application or release of pressure against the back. Such chairs, as heretofore made, commonly embody a pivotally mounted back, spring means for urging the back forwardly, and frictional brake means for opposing movement of the back in either direction.

It is the object of our invention to improve the construction and operation of self-adjusting chairs. More specifically, it is our object to provide a self-adjusting chair in which the back-control mechanism will so operate that, throughout the entire range of back movement, the load on the back can vary considerably without resulting in any displacement of the back. Another object of the invention is to produce a self-adjusting chair in which the effort required to depress the back from any given position will be the same irrespective of the direction in which the back was moved to attain that position. A further object of the invention is to construct a self-adjusting chair having back-controlling mechanism which can be readily adjusted to meet the desires of the occupant of the chair.

In carrying out our invention, we mount the chair-back for pivotal adjustment about an axis located approximately at the intersection of the load-supporting surfaces of the seat and back. The back is connected as through a link with a reciprocable wedge-shaped brake member against the obliquely disposed faces of which a pair of brake-shoes bear. In the preferred form of construction, one of such shoes is stationary with respect to the base frame of the chair, while the other shoe is mounted for free swinging movement at an intermediate point of a lever pivoted to the base frame. A spring, which is desirably adjustable, acts against such lever to force the associated brake-shoe against the adjacent side of the brake member. The arrangement of the parts is such that the resultant of the forces exerted by the brake shoes on the obliquely disposed sides of the brake member tends to move the back forwardly toward an upright position. Desirably, the lever is so shaped and disposed that as it swings changes in the lever arm of the force exerted on it by the lever-mounted brake-shoe will at least partially offset changes in the force exerted on the lever by the spring.

The accompanying drawing illustrates our invention: Fig. 1 is a vertical section on the line 1—1 of Fig. 2 showing the back-controlling mechanism in side elevation; Fig. 2 is a fragmental vertical transverse section on the line 2—2 of Fig. 1 showing the right side of the chair; and Fig. 3 is a similar section but on the line 3—3 of Fig. 1 and showing the left side of the chair.

The chair shown in the drawing comprises a

pair of generally similar side frames 10 rigidly interconnected by front and rear stretchers 11 and 12. The side frames 10 and the stretchers 11 and 12 constitute a base structure supporting a spring unit 13 on which a seat cushion 14 rests. The chair also embodies a back having a back frame 15 the front of which is covered by cushioned upholstery 16. To each side of the back frame 15 and near the lower end thereof there is secured a mounting bracket 17 pivotally connected to the adjacent side frame 10 as by means of a shaft 18 mounted in such side frame. The two shafts 18 on the two side frames 10 are located in alignment with each other approximately at the intersection of the load-supporting surfaces of the seat and back cushions 14 and 16 when the chair is occupied.

At each side of the chair and within the side frame 10, we dispose mechanism for controlling the position of the chair-back about the axis of the shafts 18. These mechanisms are the same, and hence only one of them will be described. Referring to Fig. 1, it will be obvious that each of the brackets 17 is connected at a point displaced from the shaft 18 with one end of a link 20 which extends forwardly and downwardly for pivotal connection with a brake member 21. Such brake member is generally wedge-shaped and has a pair of plane brake surfaces disposed at an acute angle to each other. One of such surfaces is disposed horizontally to rest on a brake shoe 22 mounted in a horizontal position on the side frame 10. The other surface, which is inclined forwardly and downwardly, co-operates with a brake shoe 23 pivotally mounted, as on a pin or rivet 24, at an intermediate point of a lever 25. Both of the brake shoes 22 and 23 are faced with friction material such as the brake-lining material commonly used in the brakes of automotive vehicles.

The lever 25 has its lower end pivotally connected to the side frame 10 in advance of the brake shoe 22 and extends generally rearwardly and upwardly, being connected at its upper end to the front end of a tension spring 27 the rear end of which is connected with the side frame 10, desirably through an adjusting device whereby the force exerted on the lever 25 by the spring may be varied. As shown, such adjusting device takes the form of a cable 28 which is connected to the rear end of the spring 27, passes over a pulley 29 rotatably mounted in the side frame 10, and extends downwardly from such pulley to a transversely extending horizontal shaft 30 to which the lower end of the cable 28 is secured. The shaft 30 extends completely across the chair, and the cables 28 of both back-controlling mechanisms are secured to it. Inside one of the side frames 10, a worm wheel 32 is secured to the shaft 30 in position to mesh with a worm 33 rotatably supported in a bracket 34 secured to

the adjacent side frame 10. An operating knob 35 may be provided for rotating the worm 33.

It will be apparent from the construction as so far described that the spring 27, by urging the upper end of the lever 25 rearwardly, will cause both brake shoes 22 and 23 to bear against the respectively adjacent, obliquely disposed sides of the brake member 21. If the contact of the brake shoes with the sides of the brake member were frictionless or substantially so, the resultant of the pressures exerted by the brake shoes on the brake member would be directed upwardly and rearwardly and, transmitted to the chair-back through the link 20, would urge the back forwardly. However, contact of the brake shoes with the brake member is not frictionless; and to the extent that it is not frictionless, the effect of brake-shoe pressure on the brake member in urging the chair forwardly is reduced. By properly co-ordinating the angle between the brake surfaces of the brake member 21 with the coefficient of friction between the brake shoes and those surfaces, the effectiveness of the spring 27 in urging the chair-back forwardly can be reduced to any extent desired or eliminated entirely. Desirably, the angle between the surface of the brake member 21 is such that the spring 27 has little if any effect in urging the chair-back to swing forwardly about the shafts 18. When this is the case, we employ means such as a spring 37 acting between the brake member 21 and a fixed abutment on the side frame 10 to urge the brake member 21 rearwardly and hence to bias the chair-back for forward swinging.

The chair-back is shown in full lines in Fig. 1 in the position it assumes when the chair is not occupied or when the occupant of the chair is not leaning against it with any substantial effort. In this condition, the chair-back is inclined slightly to the rear, and the force of gravity acting on it would normally tend to cause it to swing rearwardly. However, rearward swinging of the back would entail forward movement of the brake member 21 and extension of the two springs 27 and 37, as well as the overcoming of the friction between the brake member 21 and the two brake shoes 22 and 23. As a result of the effect of friction and of the forces exerted by the two springs, the chair-back will remain in the position indicated until a rearward pressure greater than a predetermined value is exerted against it. If an occupant of the chair desires to increase the rearward inclination of the back, he merely increases the pressure against it to an extent sufficient to overcome the effects of the two springs 27 and 37 and of the friction exerted on the brake member 21 by the two brake shoes 22 and 23. If desired, the occupant may apply sufficient pressure to the chair-back to swing it into a substantially horizontal position, such as is indicated in dotted lines in Fig. 1. Having adjusted the chair-back to the desired degree of inclination, the occupant may then reduce considerably the pressure exerted against it without permitting forward swinging of the chair-back, for the friction between the brake member and brake shoes will oppose such forward swinging. If the parts are properly proportioned, release of all rearward and downward pressure from the chair-back will cause it to move slowly toward its normal, nearly upright position.

It will be apparent from Fig. 1 that the fric-

tion mechanism imposes a much greater resistance to lowering of the back than to raising of the back. In fact, by properly coordinating the angle between the faces of the brake member 21 with the coefficient of friction between the brake member and the brake shoes 22 and 23, the friction mechanism can be constructed to exert substantially no opposition to raising of the back, or even to assist raising of the back, while still offering a substantial resistance to lowering of the back. As a result, the supplementary spring 37 can be much lighter than it would otherwise have to be. It will also be noted that no movement of the back can occur without movement of the brake member 21 relative to the shoes 21 and 22, and that the brake mechanism therefore functions to hold the back in fixed position until the force applied to it becomes great enough to overcome the effect of friction between the brake member and shoes.

We claim as our invention:

1. In a self-adjusting chair, a seat, a back pivotally mounted on a horizontal axis for swinging movement relative to the seat, a brake member having brake surfaces disposed at an acute angle to each other, brake shoes respectively engaging said surfaces, yielding means acting to urge said shoes toward each other, said brake member being movable in the plane of said acute angle and toward the apex thereof to force the brake shoes apart and away from such apex to permit the brake shoes to approach each other under the influence of said yielding means, and mechanism interconnecting said back and brake member to cause said brake member to force said shoes apart when the back is swung rearwardly from a vertical position.

2. The invention set forth in claim 1 with the addition of a second yielding means urging said back forwardly toward a vertical position.

3. The invention set forth in claim 1 with the addition that said yielding means is adjustable.

4. In a self-adjusting chair, a base, a seat on the base, a back pivotally supported from said base on a horizontal axis for swinging movement relative to said seat, a link pivotally connected to said back in rear of the back-axis and extending forwardly and downwardly, a brake shoe secured to said base in a generally horizontal position, a brake member having two brake surfaces disposed at an acute angle to each other, said brake member being connected to the front end of said link and disposed with one of its brake surfaces engaging said brake shoe and the other inclined forwardly and downwardly, a lever fulcrumed on said base in advance of said brake shoe and extending upwardly, a second brake shoe pivotally mounted on said lever and engaging the inclined face of the brake member, and a spring for urging the upper end of said lever rearwardly.
